UNITED STATES PATENT OFFICE.

ELLA N. GAILLARD, OF NEW YORK, N. Y.

COMBINED PAPER-WEIGHT, CALENDAR, AND MUSICAL WATCH.

SPECIFICATION forming part of Letters Patent No. 402,916, dated May 7, 1889.

Application filed September 8, 1888. Serial No. 234,862. (No model.)

To all whom it may concern:

Be it known that I, ELLA N. GAILLARD, a citizen of the United States, and a resident of New York city, in the county and State of New York, have invented certain new and useful Improvements in a Combined Musical Watch, Paper-Weight, Calendar, and Pen-Extractor, of which the following is a specification.

My invention consists of a combined music-box and calendar having the form and exterior characteristics of a stem-winding watch, together with the dial, indices, and hands adapted for the purpose of a calendar, with contrivances for operating one of the hands and winding up the music by the stem of the watch, and being adapted for the purposes of a paper-weight, and also provided with a pen-extractor for removing worn-out pens from the holders, all as hereinafter fully described, reference being made to the accompanying drawings, in which—

Figure 1 is a horizontal section of my improved combined musical watch, paper-weight, and calendar. Fig. 2 is a transverse section of the same. Fig. 3 is a face view of the device, and Fig. 4 is a detail showing the adaptation of the stem of the winder for a pen-extractor. Fig. 5 is a face view showing modifications.

In any approved case, *a*, more or less resembling a watch-case and having a dial, *b*, and usual watch-crystal, *c*, I arrange the ordinary works of a music-box, as the pin-barrel *d*, comb *e*, barrel-driving spring *f*, gear-train *g*, regulating-fly *h*, and its driving-train *i*, together with the winding-stem *j*, for winding up the spring, which spring is connected with the driving-train *g* by the usual ratchet, *k*, and pawl *l* of such works, enabling the winding of the spring without turning the rest of the works backward, and with the dial *b*, having the exterior circle of numbers, *m*, for the days of the month, also the intermediate circle of letters, *n*, indicating the names of the months, and the inner circle of letters or names, *o*, of the days of the week. I arrange the pointer *p* for the circle *m*, pointer *q* for circle *n*, and pointer *s* for inner circle, *o*, fitting pointer *p* to the sleeve *t* and gearing said sleeve with the stem *j* by the worm-gears

u, shaft *v*, and the wheel *w* on said shaft, with which the stem-pinion *x* gears when the stem, which is made to shift lengthwise in its bearing-hub *y*, is shifted to the innermost position, and with the other pointers, *q* and *s*, fitted to sleeve *q'* and post *s'*, respectively. I arrange the ratchets *a' b'*, pawl-levers *c'* and *d'*, and the pawls *e'* and *f'*, respectively, for shifting them by moving the outer ends of the pawl-levers, which are made to project slightly at the outer ends through slots in the case, allowing them the requisite amount of swing for so shifting the pointers, the levers being worked one or more times for each shift of the pointers, according as the ratchets have to be shifted the range of one or more teeth for each movement of the pointers.

The pinion *g'*, by which the spring of the music-works is wound up, is set in a plane *z* wherein the stem-pinion *x* gears with it when disconnected from the wheel *w* by shifting the stem to its outermost position, which arrangement is contrived so that the stem may be utilized for turning either the pointer or the winding-up mechanism without moving the other. The stem has a couple of grooves, *h'*, in which a small spring, *i'*, drops to retain the stem in whichever position it may be set.

I make a split or divided knob of the winding-stem, with one of the parts jointed, as in Fig. 4, and fitted with an opening-spring, *l'*, if desired, to utilize the knob as a grip device, forming a convenient and effective pen-extractor, whereby old ink-coated pens may be pulled out of the holders without soiling the fingers.

I may of course make good use of the calendar and paper-weight without having the music-works included; but its use is preferable as an attractive feature, and it is serviceable, also, because of the additional weight it affords for the purposes of a paper-weight; and instead of arranging the indices *m*, *n*, and *o* on the dial and employing the pointers, it is plain that I may employ disks *m'*, *n'*, and *o'* under the dial, carrying the indices and showing the figures through openings *p'* in the dial, the disks being attached to the sleeves *t*, *q'* and posts *s'*, respectively, and being turned by the stem and ratchets same as when carrying the pointers, the arrangement

of apparatus being the same except the substitution of the disks having the indices for the pointers and the indices on the dial, as represented in Fig. 5, and it will be readily understood from the foregoing that endless bands carrying indices and working on rollers to show the figures or characters through openings in the dial may be in like manner worked with the stem and ratchets.

10 What I claim, and desire to secure by Letters Patent, is—

15 1. The improved combined paper-weight and calendar, comprising, in combination, the stem-winder-watch case, the dial, the calendar-indices, the index-indicators, winding-stem geared with one of the index-indicators, and ratchet mechanism geared with one or more other index-indicators, substantially as described.

2. The improved combined paper-weight 20 and calendar, comprising, in combination, the stem-winder-watch case, inclosed music-works geared with the winding-stem, the calendar-indices, the index-indicator geared with the winding-stem, and one or more index-indicators having ratchet-shifting mechanism, substantially as described.

3. The combined stem-winding calendar and paper-weight, winding-stem, and gripping-stem-knob pen-extractor, substantially as de- 30 scribed.

Signed at New York city, in the county and State of New York, this 7th day of August, A. D. 1888.

ELLA N. GAILLARD.
